UNITED STATES PATENT OFFICE.

ARTEMAS E. COLBURN, OF BELLINGHAM, WASHINGTON.

DESIGN FOR A SPOON OR FORK.

No. 38,715.

Specification for Design.

Patented Aug. 6, 1907.

Application filed May 28, 1907. Serial No. 376,217. Term of patent 7 years.

To all whom it may concern:

Be it known that I, ARTEMAS E. COLBURN, a citizen of United States, residing at Bellingham, in the county of Whatcom and State of Washington, have invented a new, original, and ornamental Design for Spoons or Forks, of which the following is a specification, reference being had to the accompanying drawing, forming a part thereof.

The figure is a plan view of a spoon, or fork showing my design.

I claim:

The ornamental design for a spoon or fork, as shown.

ARTEMAS E. COLBURN.

Witnesses:

P. M. LIDDY,

O. H. FRAZIER.
